UNITED STATES PATENT OFFICE.

ALLEN E. OSTRANDER, OF RIDGEWOOD, AND ERNEST R. SCHROEDER, OF PATERSON, NEW JERSEY, ASSIGNEES TO AMERICAN CAR AND FOUNDRY COMPANY, OF ST. LOUIS, MISSOURI, A CORPORATION OF NEW JERSEY.

CAR-DOOR-OPERATING MECHANISM.

1,244,768.

Specification of Letters Patent. Patented Oct. 30, 1917.

Application filed October 5, 1916. Serial No. 123,898.

To all whom it may concern:

Be it known that we, ALLEN E. OSTRANDER and ERNEST R. SCHROEDER, residing at Ridgewood, Bergen Co., State of New Jersey, and Paterson, Passaic county, State of New Jersey, respectively, and being citizens of the United States, have invented certain new and useful Improvements in Car-Door-Operating Mechanism, of which the following is a full, clear, and exact description, such as will enable others skilled in the art to which it appertains to make and to use the same, reference being had to the accompanying drawings, which illustrate the preferred form of the invention, though it is to be understood that the invention is not limited to the exact details of construction shown and described, as it is obvious that various modifications thereof within the scope of the claims will occur to persons skilled in the art.

In said drawings:

Figure 1 is a side elevation of that part of a cane car which extends from one end 25 of the car toward the other end for a distance great enough to include one of the side doors of the car;

Fig. 2 is an enlarged elevational view of one of the door locks and its associated parts 30 as applied to the car side in Fig. 1;

Fig. 3 is a transverse section through the car sill and door operating mechanism, showing the lock depicted in Fig. 1, but with one of its supporting brackets removed;

Fig. 4 is an inverted plan view of Fig. 3, the swing door being omitted;

Fig. 5 is a side elevation of the slotted door-retainer arm as viewed from the plane 40 indicated by line 5-5 of Fig. 2, the direction of vision corresponding to that of the arrows;

Fig. 6 is a side elevation of the interlocking bushing associated with the door-retainer arm, being viewed in a direction opposite that of the arrows of line 5-5 of Fig. 2;

Fig. 7 is an elevational view of the double bushing bearing shown as mounted on 50 the side sill of Fig. 1 near the latticed corner post;

Fig. 8 is a horizontal section taken on the line 8-8 of Fig. 1, the car floor being omitted; and

Fig. 9 is a cross sectional view through the 55 side sill, showing the double bushing bearing and its supporting bracket at a right angle to the position of those parts shown in Fig. 7.

In train operating various types of cars 60 are used in which a plurality of doors are present in a car, which doors are maintained in their closed positions by suitable door-operating means. In former practice it has been quite common to thread a number of 65 door-lock parts onto an operating shaft, after which the shaft is securely mounted upon a rigid portion of the car structure. After the installation of such a car door-operating mechanism, it is necessary to remove 70 the shaft and its appendages in order to repair a single door-lock and it is often the case, where a series of door locks are operated by the same shaft, that the failure of one lock to operate necessitates the removal 75 of all of the locks, and consequently involves a great deal of unnecessary labor and expense.

It is a purpose of the present invention to provide a door-operating means which 80 will eliminate so wasteful a procedure.

In its broad aspect, the invention is applicable to those types of cars which have side, end and bottom doors, and may also be advantageously used in connection with the 85 doors of hopper cars. A special application of the invention, however, is its use in connection with cane cars in which there are a number of doors successively arranged on one side of the car, though it is to be understood 90 that its use is equally desirable where there are doors on both sides of the car, or at the ends thereof.

The invention contemplates a door-operating mechanism which includes door locks, 95 each comprising a plurality of parts, which, when in assembled condition and mounted so as to be supported by a car structure, are kept in co-operative relation without the literal attachment of one part to another, or 100 of any of the parts to the operating shaft. Where it is desirable, but one door-lock may

be associated with a door, and there may be a number of doors each controlled by a single door-lock, all of the locks being adapted to be simultaneously actuated by appropriate means. In the case of a series of doors, each under the control of a single lock, it is thoroughly feasible to operate each lock independently, permitting the opening of only such door, or doors, as it is wished to place in position for discharging lading.

In any of the arrangements referred to, but especially in the instance of a considerable number of the door-locks being affiliated with but a single door, the operable parts of any lock may be disassembled and removed from the operating shaft without demounting the latter, and in no way disturbing the balance of the door-operating mechanism. Thus, if any lock becomes broken or for any reason refuses to operate satisfactorily, it may immediately be removed by one of the train crew, for example, and its absence will not affect the efficiency of the door-operating mechanism.

A few extra door-lock parts may be kept in available places and can be substituted in a lock on a car on which the corresponding part or parts are faulty. As a wrench is the only necessary tool to remove and replace the parts of a door-lock, any one obtaining one and the necessary extra part or parts, can restore the lock to its normal condition and it is quite unnecessary to 35 turn a car to the repair shop for the restoration of the door-operating mechanism to a perfect condition.

Such features as have not already been touched on will become self-evident herein-after, assuming their obvious places in this invention.

Referring to the drawings, and first to Fig. 1 in which an end portion of a cane car is illustrated, 1 indicates the side sill of a car which may, as shown, be a commercially rolled channel that extends from the end sill 2 at one end of the car to the end sill at the opposite end of the car, (not shown), a suitable flooring 3 being supported by an underframe including these members. Near the illustrated end sill 2 is a latticed corner post comprising a pair of vertically extending angles 4 and 5, angle 4 having the direction of a plumb line and angle 5 inclining 55 inwardly as it progresses upwardly until the upper extremities of both angles 4 and 5 are substantially in contact, said angles being strongly united by lattice bars 6. Secured to the upper ends of angles 4 and 5 60 of the latticed corner post, is a horizontal top angle or side plate 7 which may, or may in effect, extend from one end of the car to the other. Spaced rearwardly a considerable distance from the latticed corner post, is a partition post 8 which, like the

corner post, is rigidly combined with the side sill 1 and top angle or side plate 7. The remainder of the car side may be made up of similar subdivisions forming the side structure of the car. The spaces outlined by the side sill, top angle 7 and the corner and partition posts, are each closed by a swing door of gate-like construction, said door comprising a bottom door-stiffener 9, here shown to be a commercial angle though it may have other form, door posts 10 and a top door-stiffener 11 of angle shape. Door posts 10 may conveniently be I-beams and to the upper extremities of the webs thereof is secured hinge plates 12 perforated, and hung on depending eyes 13 secured to the horizontal flange of the top angle or side plate 7. Top door-stiffener 11 is directly riveted to the flanges of the door-post I-beams, while the bottom door-stiffener is secured to the lower extremities of door post 10 by angular connection plates 14 riveted to the web of door post 10 and to the horizontal flange of door-stiffener 9. A rigid swing door is thus created adapted in its closed position to be vertically arranged and which may swing outwardly toward the observer of Fig. 1 when it is desired to discharge sugar-cane or other lading from the car. At other times, when it is desired to retain lading, the swing door may be held in its closed position by any suitable number of door locks 15, four such locks being illustrated in Fig. 1.

A lock-operating shaft 16 is operably connected with each of the door-locks 15 of the set associated with a single door and extends toward the end sill 2. At the point where it is substantially opposite angle 5 of the latticed corner post, operating shaft 16 is upwardly turned and laps angle 5 for a suitable distance.

In Fig. 1, another operating shaft 16^a is illustrated and is positioned below shaft 16, extending rearwardly beyond the swing door 110 illustrated, after which it is broken away.

Shaft 16^a is the substantial duplicate of shaft 16, but extends rearwardly for the operation of other door-locks associated with the next adjacent swing door, (not shown). Door lock-operated shaft 16^a is also turned upwardly at its end in the manner that shaft 16 is, but is positioned in substantial alignment with the angle 4 of the latticed corner post. Behind each of the upturned ends of the operating shafts 16 and 16^a, are door-lock shaft link slides 17 and 17^a, each of which is quite similar to the well-known grab-irons attached to car sides. The upper and lower ends of the link slides are secured by rivets to the angles 4 and 5 of the latticed corner post, and are spaced away from the flanges of those angles that are parallel with the car sides a suitable distance to permit shaft-lock links 18 to slide vertically of the 130

link slides 17 and 17^a, as more fully illustrated in Fig. 8.

When links 18 are in the position shown in Fig. 1, they embrace both the upturned lever ends of lock-operating shafts 16 and 16^a and the link slides 17 and 17^a, and restrain the operating shaft lever ends from rotation. When the lever arms of the operating shafts are in this position, the latch 10 arms 19 of the door-locks 15 occupy the positions illustrated in full lines in Figs. 2 and 3, where it is seen that they lap the vertical flanges of the angular bottom door-stiffener 9 and prevent the door from swinging outwardly.

As best seen in Figs. 2 and 3, each door-lock 15 includes a latch arm 19 which is in the form of a casting and is provided with a hub 20 extending from one side thereof and a 20 segmental projection 21 extending from the opposite face. Associated with latch arm 19 is an interlocking bushing 22, shown to best advantage in Figs. 2 and 6, which bushing has a flange 23 and a hub 24 similar to 25 the hub 20 of the latch arm 19, and from the face of bushing 22 which is contiguous to the adjacent face of latch arm 19, extends a segmental projection 25. Door-lock operating shaft 16, which preferably is non-circular in cross section, passes through both 30 latch arm 19 and interlocking bushing 22, each of which is provided with a deep slot, designated in Fig. 5 as 26 and in Fig. 6 as 27, of a width corresponding to the thickness of 35 shaft 16, which slot, in each instance, receives shaft 16 and continues outwardly to interrupt the perimeter of the latch arm or the interlocking bushing.

Bearing brackets 28 are secured to the side 40 sill 1, being disposed one on each side of the associated latch arm 19 and interlocking bushing 22. These bearing brackets 28, as shown in Fig. 4, are angular and are perforated to receive the hubs 20 and 24 of the 45 latch arm 19 and interlocking bushing 22, respectively. Brackets 28 are preferably bolted to the side sill 1 to permit comparatively easy separation therefrom. When the parts are assembled as shown in Fig. 2, latch 50 arm 19 and interlocking bushing 22 are interlocked by reason of latch arm projection 21 extending into slot 27 of the associated interlocking bushing 22 and further by the projection 25 of interlocking bushing 22 extending into slot 26 of latch arm 19, as may 55 be readily understood by consulting Figs. 2 to 6 inclusive. With latch arm 19 and its associated interlocking bushing 22 maintained in assembled position, it will be evident from the foregoing that projection 25 of bushing 22 closes slot 26 of latch arm 19 and that projection 21 of said latch arm closes the slot 27 of bushing 22, so that shaft 16 is completely surrounded. Also the seating of projections 21 and 25 of the latch arm

and interlocking bushing in the slots of the opposing member prevent any relative rotation between the latch arm 19 and its associated bushing 22.

While both latch arm 19 and its associated 70 interlocking bushing 22 of each door-lock are being assembled, they are spaced longitudinally of the shaft so as to be non-interfering and each may be slipped onto the shaft by a movement transversely thereof, 75 after which they are moved longitudinally of the shaft in opposite directions to bring them together and into the interlocking relation just referred to. After coming into said interlocking relation, they cannot be removed by a movement transversely of the shaft for the reason that each can only at any time be removed from the shaft by movement in one direction, and as these directions are arranged perpendicular to each other, the projections 21 and 25 of the latch arm 19 and interlocking bushing 22, respectively, interfere with the withdrawal of either of these members in its proper direction, consequently once assembled in interlocking relation, the latch arm and its associated interlocking bushing of each door-lock is incapable of separation from the shaft. To render the interlocking relation permanent as long as desired, the outwardly 90 extending legs of the angular bearing brackets 28 are spaced only very slightly in excess of the combined widths of the flange 23 of the interlocking bushing 22 and the locking arm of latch arm 19, and as the outstanding 100 arms of bracket bearings 28 embrace these members, unintentional separation of them is impossible.

With the swing door closed so that the depending flange of its bottom stiffener 9 lies 105 substantially against the outer face of side sill 1, as shown in Fig. 3, the operating handle of shaft 16 may be vertically arranged as in Fig. 1. When it is so arranged, latch arm 19 of each door-lock 15 will be in the 110 full line position of Fig. 3; and these latch arms will effectively prevent the opening of the swing door. Occasion arising for discharging the sugar-cane, or other lading, from the car, the lever arm of door-lock operating shaft 16 may be rotated through substantially 180° to carry the latch arm 19 of each door-lock into the dot and dash position indicated in Fig. 3, whereupon said latch arms no longer obstruct the bottom stiffener 120 9 and swing door may be opened to discharge the lading. Before the operating handle of shaft 16 can be turned through the distance indicated, however, that one of the lock links 18 associated with the operating 125 handle of that shaft, shown in Figs. 1 and 8, must be raised to clear the upper end of the operating handle of said shaft 16, after which the operating handle in question may be revolved to extend downward in an op- 130

posing direction where it will be unobtrusive. After the lading has been discharged, the swing door may be returned by gravity to the position illustrated in Figs. 1 to 3 inclusive and the operating handle of shaft 16 may be returned to the position illustrated in Fig. 1, whereupon lock link 18 associated with that operating handle, which will have dropped by gravity, may be raised and subsequently lowered to embrace both the link slide and operating handle in question. Latch arm 19 of each of the door locks 15 will, of course, be returned to the full line position by this action and the swing door 15 will be firmly retained against opening until a repetition of the operation just set forth takes place.

Another swing door, not shown but similar to that illustrated, may be opened and closed in like manner by actuating lower door-lock operating shaft 16^a.

The door-lock bearing brackets 28 form supports for the hubs of the divisible latch comprising the latch arm 19 and interlocking bushing 22, and, therefore, also a support for the operating shaft 16. It is, however, desirable to support both shafts 16 and 16^a at other points than at the door-locks and for this purpose other bearings 30 are provided, such as the double bearing 29 near the latticed corner post and the single bearing 30 for shaft 16^a, rearwardly spaced a suitable distance therefrom. Both the single and double bearings are of substantially the same character and the double bearing 29 comprises a bracket 31, bolted or otherwise secured to side sill 1, and upper and lower bearing bushings 32 revolvably mounted in the outstanding arm of the bracket 31, as clearly seen in Figs. 7 and 9. Each bearing bushing is provided with a flange 33 of greater diameter than the bracket aperture, through which the hub-like portion of the bearing bushing extends. Said bearing bushings 32 are freely slideable out of bearing bracket 31, except when cotter or other pins 34 are inserted through door-lock operating shaft outside the bushing flange 33. With the cotter pins 34 in place, each bearing bushing 32 has its flange confined between the outstanding arm or leg of its supporting bracket 31 and the cotter pin, and consequently cannot become disengaged from said bracket 31.

It will be noticed in Fig. 8 that the lock-link for lower operating shaft 16^a is of greater length than that for upper door-lock operating shaft 16, and shaft 16^a has its extremity bent outwardly into another plane. As a result, either operating shaft 16 or 16^a may be operated independently of the other shaft and without interference one from the other.

One of the important features of this invention consists in the ability of repair-

ing a broken or unsatisfactorily operating door-lock without returning the car to a repair shop or calling for the assistance of a skilled mechanic. Assuming that the door-lock shown in Figs. 2 to 6 inclusive is in unsatisfactory condition and it is desired to replace either the latch arm 19 or its associated interlocking bushing 22, or to remove these members entirely, it is only necessary to remove the bolts securing one of the bearing brackets 28, thus disconnecting that bearing bracket with the side sill 1. After such disconnection, said bearing bracket 28 may be slid longitudinally of shaft 16, and latch arm 19 and its interlocking bushing 22 are also so slid and separated in the sliding action a sufficient distance to withdraw the projection 21 of latch arm 19 and projection 25 of the associated interlocking bushing 22 from the slots of these co-operative members so that each is freed from the other. This being done, latch arm 19 may be removed by being drawn transversely off operating shaft 16 without hindrance and, similarly, interlocking bushing 22 may be withdrawn, as is thoroughly evident from Figs. 5 and 6. A new latch arm and its associated bushing, or one or the other if both are not impaired, may be substituted and slid onto the shaft, as shown in Figs. 5 and 6, after which they are pushed longitudinally of the shaft 16 so that they are brought into the interlocking relation illustrated in Fig. 2. The bearing bracket 28 that was detached to permit the removal of the door latch and its bushing, is then brought back to its normal position and is again bolted to side sill 1. The door-lock is then restored to its original operative condition, which may be accomplished by no more skilled a mechanic than one of the train crew. In case the breakage or disaffection of the door-lock takes place while the train is in transit, the latter may be stopped and the latch arm 19 and its associated bushing 22 removed, as described, and the train may then resume its travel without in any way impairing the efficiency of the door-restraining and locking means.

What we claim is:

1. In combination in a railway car, a hinged door, a door-lock therefor and a door-lock-operating shaft, said lock comprising suitably sustained supporting brackets and co-operative shaft-girdling door latch members operable by said shaft and capable of withdrawal therefrom transversely thereof.

2. In combination in a railway car, a hinged door, a door lock therefor and a door lock-operating shaft, said lock comprising shaft-supporting and door-latch members retained in such position as to be inseparable from said shaft and being capable of separation and so formed that said latch mem-

bers may be detached from said shaft by movement transversely thereof after such separation.

3. In combination in a railway car, a hinged door, a divisible door-locking latch and a door latch-operating shaft, said latch being maintained inseparable without actual connection of its divisible portions to be undetachable from said shaft and adapted to be separated and removed transversely of said shaft.

4. In combination in a railway car, a hinged door, a plural-part door-locking latch and a door latch-operating shaft, the members of said latch being individually freely removable from said shaft transversely thereof but being interlocked when assembled to be incapable of withdrawal from said shaft in any direction.

20 5. In combination in a railway car, a hinged door, a divisible door-lock, a door lock-operating shaft, said lock comprising door latch and shaft-supporting members, and means for causing the latter members to maintain said latch members in coöperative and shaft-confined relation, said means being adapted to be rendered ineffective, the door lock being divisible thereafter and said latch members then being removable transversely of said shaft.

6. In combination in a railway car, a hinged door, a door lock-operating shaft, a door lock comprising supporting brackets and inter-dependent latch members none having actual attachment to said shaft, and means so correlating said brackets and latch members that the latter co-act and are shaft-confined, said brackets and latch members being separable longitudinally of said shaft and said latch members being removable transversely thereof after a nullification of said correlating means.

7. In combination in a railway car, a hinged door, a door latch comprising associated members socketed one into the other in a manner preventing relative rotation of said members, a latch-operating shaft to which said latch members are confined by their socketed relation adapted to rotate said members in unison, said members being releasable from said shaft intermediate its ends by movement longitudinally and transversely thereof.

8. In combination in a railway car, a hinged door, a door lock-operating shaft and a door lock comprising door latch members and supporting brackets socketed into each other to be shaft-confined, said latch members being socketed so as to be relatively non-rotative and revoluble in said brackets and said brackets and latches being separable longitudinally of said shaft and said latches being removable transversely of the shaft after such separation.

65 9. In combination in a railway car, a

hinged door, a door latch-operating shaft, a door latch comprising a plurality of associated shaft-embracing members each slideable onto and off said shaft in a single direction that is different from the direction of sliding of its associated member, and means on each member preventing its associated member from sliding off said shaft.

10. In combination in a railway car, a hinged door, a door latch-operating shaft, a door latch comprising a plurality of associated shaft-embracing members each slideable onto and off said shaft in a single direction that is different from the direction of sliding of its associated member, and means on each member preventing its associated member from sliding off said shaft, said members being separable to unrelated said means and become subject to removal from said shaft.

85 11. In combination in a railway car, a hinged door, a door lock-operating shaft, a door lock comprising associated latch members assembled so that each of said members co-acts with its associated member to prevent the same from being disconnected from said shaft when said members are in the state of assembly specified, and means preventing removal of said latch members from either end of said shaft, said associated latch members being capable of being placed in irrelative positions and then removed from said shaft.

12. In combination in a railway car, a door, a non-circular door lock-operating shaft, and a door lock comprising supporting brackets mounted on the car structure and a latch comprising a latch arm and a co-operative bushing each provided with a shaft-receiving slot conformed to the shaft section and projections on said latch arm and bushing extending, respectively, into the slots of said bushing and arm and preventing either from being withdrawn from said shaft, said arm, bushing and brackets being capable of separation longitudinally of said shaft to permit said arm and bushing to be withdrawn transversely thereof.

13. In combination in a railway car, a door, a non-circular door lock-operating shaft, and a door lock comprising supporting brackets mounted on the car structure and a latch comprising a latch arm and a co-operative bushing each provided with hubs revolubly supported in said brackets and also with a shaft-receiving slot conformed to the shaft section and projections on said latch arm and bushing extending, respectively, into the slots of said bushing and arm and preventing either from being withdrawn from said shaft, said arm, bushing and brackets being capable of separation longitudinally of said shaft to permit said arm and bushing to be withdrawn transversely thereof.

14. In combination in a railway car, a

door, a door lock therefor, a non-circular door lock-operating shaft and a support for said shaft comprising a bracket secured to the car structure and having a perforated portion, a cylindrical bushing extending through the bracket perforation and provided with a flange incapable of passing therethrough, and removable means secured to said shaft preventing the flanged end of 10 said bushing moving in a direction to allow

withdrawal of said bushing from said bracket.

In witness whereof we have hereunto set our hands in the presence of two witnesses.
